To all whom it may concern:

Be it known that I, ALBERT SELTER, a subject of the Emperor of Germany, residing at Hoboken, in the county of Hudson and State of New Jersey, have invented and produced a new and original Design for Picture-Frames, of which the following is a specification.

The leading feature of my design consists of an approximately rectangular frame A,

having a central opening B for the picture and part of each side and end curved to the front and inwardly toward the central opening to form a scroll C. A bow, tassel, or other ornament D is arranged on or depends from the scroll at or near the middle thereof.
